Primary Examiner — Holly E Thurman*Assistant Examiner* — Ieisha N Price(74) *Attorney, Agent, or Firm* — Bhole IP Law; Anil Bhole; Marc Lampert(57) **CLAIM**

The ornamental design for a connector, as shown and described.

DESCRIPTION

FIG. 1 is a front perspective view of a connector according to our new design.

FIG. 2 is a top view of the design of FIG. 1.

FIG. 3 is a bottom view of the design of FIG. 1.

FIG. 4 is a front view of the design of FIG. 1.

FIG. 5 is a rear view of the design of FIG. 1.

FIG. 6 is a left side view of the design of FIG. 1.

FIG. 7 is a right side view of the design of FIG. 1.

FIG. 8 is a rear, left side perspective view of the design of FIG. 1.

FIG. 9 is a left side, front perspective view of the design of FIG. 1.

FIG. 10 is a right side, rear perspective view of the design of FIG. 1; and,

FIG. 11 is a front, right side perspective view of the design of FIG. 1.
